CLARENCE T. ROTTLER, OF SEATTLE, WASHINGTON

MEANS FOR HOLDING A CUTTER HEAD WHILE ITS CUTTERS ARE BEING SHARPENED

Application filed November 5, 1929. Serial No. 405,008.

My invention relates to improved means by which a rotary cutter head may be securely held while the several cutters thereof are successively and properly sharpened by a hone manually operated in the usual manner. One object of the invention is to construct such a holding device that it may be detachably connected with two of the projecting cutters or blades of the head without in any way interfering with the proper application of the hone to the cutting edge of one of the other cutters.

A further important object of the invention is to provide a holding device which will accurately and securely hold the cutter head in proper position for the sharpening of cutter blades associated with the head, without requiring any manual adjustments of the holding device.

Another and quite important object of the invention is to so construct the device that the direction of movement of the hone cannot, by carelessness or inattention on the part of the workman, be so changed as to tend to destroy or impair the necessary bevel across the outer face of the lower end of the cutter, such for example as the bevel shown at (13) in the Letters Patent No. 1,522,145, granted to me on January 6, 1925,—a cutter head of the general character shown in that patent being such as the present invention is primarily designed to be used with.

The above objects I accomplish by the construction and arrangement shown in the drawing and hereinafter more particularly described. That which I believe to be new will be set forth in the claims.

In the drawing:

Fig. 1 is a top or plan view of my improved hone guide connected with a rotary cutter head, and showing also a honing implement in position alongside of the head with the sharpening element or hone in contact with a blade or cutter that is to be sharpened,—the bar-shaped handle of the implement being partly broken away.

Fig. 2 is a view of the same parts as in Fig. 1, but showing an edge view of the hone guide.

Fig. 3 is a perspective view of the hone guide.

Fig. 4 is a perspective view of the honing implement; and

Fig. 5 is a cross-section through the hone and its frame.

Referring to the several figures of the drawing wherein corresponding parts are indicated by the same reference characters, (10) indicates a rotary cutter head that is preferably of the same general type shown and described in my aforesaid Letters Patent. As here shown it is provided with four blades or cutters (11) set 90 degrees apart and adapted to be projected and held by any suitable means. The outer end of each blade is beveled in the usual manner, as clearly indicated in Fig. 1, and the lower portion of this beveled end is additionally beveled as indicated at (12) in Fig. 2, such additional beveling also inclining upwardly from front to rear as indicated by the dotted representation of the central one of the cutters shown in said Fig. 2. Particular attention is here called to this bevel (12) as it is one of the objects of the invention to ensure that in the use of the sharpening implement its character shall not be destroyed or impaired.

As best shown in Fig. 3, the sharpening implement that has been referred to comprises a hone (20) secured in any appropriate manner in a frame (21) and provided at one end with a comparatively long handle (22) which, in the form here shown, is a cylindrical bar.

The guiding device for the sharpening implement comprises a base (30) that will preferably be made of a single piece of sheet metal. At one end thereof are formed two spaced apart ears, (31—31) that stand at right angles to the base, said ears being integral with and bent upwardly from the end of the base or plate, and at some distance therefrom, and preferably cut and punched from and integral with the base are two other and similar ears (32—32), the distance between these two pairs of ears being sufficient to allow a head such as (10) to fit snugly between them. These two pairs of ears constitute seats for the reception of a pair of the projecting cutters 11 without necessitating any manual adjustments. The space between each pair of ears is just wide enough to receive one of

the projecting cutters (11). When a head is so positioned on the base, it will be evident that it will be securely held in position without the necessity of any manual adjustments.

5 At the end opposite that where are formed the ears (31), and at right angles to the base, the base (30) is turned to form a flange (33), that extends in the opposite direction from that of the ears. This flange is also extended 10 laterally from the base (30) and in its outer end is formed a comparatively deep notch, (34) in which the handle member (22) of the sharpening implement, is adapted to be movably mounted.

15 In use, a head (10) is to be placed between the two pairs of ears (31) and (32) with two of its oppositely-located cutters holding it there by reason of their entrance into the 20 spaces between the two pairs of ears. The workman will then ordinarily hold the cutter and base in one hand, in approximately the position shown in Fig. 2, which will bring the cutter (11) that stands parallel with the base flange (33) in convenient position to 25 have the hone applied to it. Before applying the hone, the handle member (22) is placed in the notch (34), such notch being large enough not to interfere in any way with the application of the hone to the cutter, either 30 by a lengthwise or sidewise movement of the hone or by a combination of such movements. The extension of the flange laterally, however, in the same direction as the cutter that 35 is being sharpened, and the engagement by the bar (22) of the notch in that flange, absolutely prevents the hone from being so directed as to impair the small additional bevel (12) that is so important to the performance 40 of proper work by the cutter. By reason of the handle bar being so held against being shifted bodily to a position opposite the base (30) the movement of the hone, when operating upon the bevel portion of the cutter must 45 be in the general direction of that bevel, as will be made clear by an inspection of Fig. 2.

What I claim as new and desire to secure by Letters Patent is as follows:

50 1. A device of the character specified comprising a base, spaced seats on the base into which a plurality of cutters that project from a cutter-head are positioned to prevent movement of the cutter-head relative to the base, and means carried by said base for movably supporting the handle of a cutter-sharpening implement and preventing lateral bodily movement of such handle.

55 2. A device of the character specified comprising a base, oppositely-located ears on the base adapted to engage two cutters that project from opposite places on a cutter-head and thereby prevent movement of the cutter head relative to the base, and means carried by said base for movably supporting the handle of a cutter-sharpening implement and

restraining lateral bodily movement of such handle.

3. A device of the character specified comprising a base, means for detachably holding a cutter-head connected to said base near one end thereof, and a support adjacent the other end of the base for the handle of a cutter-sharpening implement, said support having a notch formed therein for such handle to rest in and permitting free longitudinal and swinging movements of the handle but restraining lateral bodily movement of the handle.

4. A device for holding a cutter head having a plurality of cutter blades, comprising a base having sharpening device guide means, and spaced pairs of lugs bent out from said base and adapted to be arranged upon opposite sides of said head, the lugs of each pair being spaced apart to receive therebetween a blade of said head and being arranged to receive and hold said head against movements induced by the sharpening operation.

5. A device of the character described comprising a single sheet of material having a pair of spaced apart angularly disposed lugs struck out therefrom, a second pair of spaced apart angularly disposed lugs formed from one end of said sheet and spaced from said first pair of lugs, and the opposite end of said sheet of material having an angularly disposed guide flange formed therefrom.
